UNITED STATES PATENT OFFICE.

FRANCIS J. COLE, OF SCHENECTADY, NEW YORK.

VESTIBULE FOR LOCOMOTIVES AND TENDERS.

1,414,459.

Specification of Letters Patent. Patented May 2, 1922.

Application filed December 21, 1921. Serial No. 523,882.

To all whom it may concern:

Be it known that I, FRANCIS J. COLE, a citizen of the United States, and resident of Schenectady, in the county of Schenectady 5 and State of New York, have invented a certain new and useful Improvement in Vestibules for Locomotives and Tenders, of which improvement the following is a specification.

My invention relates to vestibule structures applied at the adjoining ends of locomotives and tenders, for the purpose of protecting the occupants from rain, wind, and intensely cold or inclement weather, and its object is to provide a structure of such character which shall be of simple and inexpensive 10 construction, ready applicability in connection with locomotives and tenders of present standard practice, and capability of maintenance of tight closure of its joints, without undue friction or liability to breakage or derangement.

The improvement claimed is hereinafter fully set forth.

In the accompanying drawings: Figure 1 25 is a side view of the adjoining portions of a locomotive and tender, illustrating an application of my invention; Fig. 2, a view, the right hand half of which is a rear elevation of the locomotive, and the left hand half, a 30 front elevation of the tender; Fig. 3, a plan view, partly in section, the right hand half being taken on the line *a a* of Fig. 2, and the left hand half on the line *b b* of the same figure; Fig. 4, an enlarged plan view, showing 35 the vertical side plate controlling means; Fig. 5, a rear view, partly in elevation and partly in section, showing the upper portion of the right hand vertical sliding plate and the upper transverse sliding plate, with their 40 respective controlling means; Fig. 6, a vertical sectional elevation, showing the upper transverse sliding plate and its relation to the tender housing flange; Fig. 7, a plan view of the same; Fig. 8, a side view of one 45 of the spring hinged arms of the sliding plate controlling means; and, Fig. 9, an end view, partly in section, of the same.

In the practice of my invention, referring 50 descriptively to the specific embodiment thereof which is herein exemplified, as applied in connection with a locomotive, indicated, as a whole, by the reference letter A, and its tender, indicated, as a whole, by the reference letter B, a stationary enclosure or 55 tender cab, 1, provided with sides and a roof, is erected upon the forward end of the ten-

der, its forward end being located adjacent to the rear end of the locomotive cab, 2, which is provided with side openings, closed by doors, 2^a. In order to protect the engine 60 crew from inclemency of weather, the spaces between these two cabs, which are necessary to permit relative movement of the locomotive and tender, are closed by automatically movable metallic appliances, hereinafter described, the rubber diaphragms applied in passenger car vestibules not being suitably adapted for use by reason of the action which would be exerted upon them by heat, 65 coal dust, and sparks.

A flange, comprising a horizontal top plate, 3, and two vertical side plates, 3^a, is secured to, and projects forwardly from, the tender cab, 1, and each of two vertical sliding plates, 4, fitted on the locomotive cab, 2, 70 and extending in transverse direction thereon, is maintained in contact with one of the vertical side plates, 3^a, of the flange, 3, 3^a. The plates, 4, fit in, and are guided by, U-shaped guides, 5, which are rigidly secured 75 to the back of the locomotive cab, by angle irons, 5^a. The vertical sliding plates, 4, are held in contact with the side plates, 3^a, by spring hinged arms, 6, which are journaled in lugs, 6^a, secured to the locomotive cab, 2, 80 by pins, 6^b, and are coupled to the plates, 4, by links, 7, thereby effecting the closure of the sides of the cabs against the entrance of cold, rain, or snow. The requisite pressure is applied to the arms, 6, and through them 85 to the vertical sliding plates, 4, by helical springs, 6^c, coiled on the pins, 6^b, and bent outwardly at one end, to engage the lugs, 6^a. The opposite ends of the springs, 6^c, are engaged with peripheral recesses in spring 90 locks, 6^d, fitted freely on the pins, 6^b, said spring locks being adjustable to impart desired tension to the springs, and being held in adjusted position by set screws, 6^e, engaging selected recesses of the spring locks, 6^d. 95

The top closure of the opening between the locomotive and tender cabs is effected by a transversely extending sliding plate, 4^a, which is maintained in contact with the horizontal top plate, 3, of the flange of the 100 tender cab, in substantially the same manner as in the case of the sliding plates, 4, and the side plates, 3^a, of the flange. The sliding plate, 4^a, extends from one of the lateral sliding plates, 4, to the other, and is guided 105 by plates, 5^b, 5^c, secured to the locomotive cab. Pressure, acting to maintain the plate,

4^a, in contact with the top plate, 3, of the tender flange, is imparted to said plate, 4^a, by spring hinged arms, 6^c, similar to the arms, 6, before described. Inasmuch as the 5 plate, 4^a, must have the capacity of a limited degree of lateral movement, it cannot be, as in the case of the plates, 4, positively connected to the spring hinged arms, and therefore the links, 7^a, through which pressure is 10 transmitted to the plate, 4^a, bear, without positive connection, on seats, 4^b, connected to the plate, 4^a. The links, 7^a, are held in vertical position by passing through perforations in fixed angle plates, 4^c. 15 The bottom of the enclosed passageway between the tender and locomotive cabs, comprises a face plate, 8, connected to the forward portion of the tender; a chafing plate, 9, abutting thereon; and a horizontal plate, 20 10, connected to the chafing plate and forming an apron or floor. The side members, 3^a, of the tender flange, are slightly recessed or cut away, to provide clearance for the chafing plate and plate, 10, in vertical movement of the locomotive, relatively to the 25 tender. Contact between the face plate and chafing plate is continuously maintained by plungers, 11, socketed in the rear of the locomotive structure and subject to the pressure 30 of helical springs, 12.

It will be seen that a construction embodying the essential features of my invention, as hereinbefore described, provides a 35 passageway between a locomotive engine and its tender, which is completely closed and protected from the weather, irrespective of all normal relative vertical or horizontal displacements, and that the structure is light, simple, and inexpensive, and is applicable in connection with any of the various 40 designs of present standard practice.

I claim as my invention and desire to secure by Letters Patent:

1. The combination, with a locomotive and 45 a tender, of a cab, at the rear end of the locomotive; side doors, closing openings for access to said cab; a cab, at the front of the tender; a forward extension, secured to the tender cab and forming an enclosure for a 50 passage way between the locomotive and tender cabs; and automatically operable means, connected to the locomotive cab, for maintaining closure of the space between said locomotive cab and said tender cab 55 extension.

2. The combination, with a locomotive and a tender, of a cab, at the rear end of the locomotive; side doors, closing openings for access to said cab; a cab, at the front of 60 the tender; a forward extension, secured to the tender cab, comprising a horizontal top

member and vertical side members, and forming an enclosure for a passage way between the locomotive and tender cabs; and automatically operable means, connected to the locomotive cab, for maintaining closure of the space between said locomotive cab and said tender cab extension. 65

3. The combination, with a locomotive and a tender, of a cab, at the rear end of the locomotive; side doors, closing openings for access to said cab; a cab, at the front of the tender; a forwardly projecting flange, secured to the tender cab, comprising a horizontal top member and vertical side members, and forming an enclosure for a passage way between the locomotive and tender cabs; and sliding plates, yieldingly connected to the locomotive cab and bearing on the members of the tender cab flange. 70 75 80

4. The combination, with a locomotive and a tender, of a cab, at the rear end of the locomotive; side doors, closing openings for access to said cab; a cab, at the front of the tender; a forwardly projecting flange, secured to the tender cab, comprising a horizontal top member and vertical side members, and forming an enclosure for a passage way between the locomotive and tender cabs; plates, fitted to slide on the locomotive 90 cab, and bearing on the members of the tender cab flange angularly thereto; and spring controlled connections, coupling said plates to the locomotive cab. 85 95

5. The combination, with a locomotive and a tender, of a cab, at the rear end of the locomotive; side doors, closing openings for access to said cab; a cab, at the front end of the tender; a forwardly projecting flange, secured to the tender cab, comprising a horizontal top member and vertical side members, and forming an enclosure for a passage way between the locomotive and tender cabs; guides, secured to the rear of the locomotive cab; plates, fitted to slide in said guides, 100 each at an angle to one of the members of the tender cab flange; and spring controlled connections, coupling said plates to the locomotive cab. 105

6. In a locomotive and cab vestibule structure, the combination of a plate, fixed on one of the vehicles; a plate, guided on the other vehicle to slide at an angle to the first specified plate; and a spring hinged arm, coupled to said last specified plate, and exerting pressure thereon in direction to maintain it in bearing on said first specified plate. 110 115
